[57] CLAIM

The ornamental design for a tire tread, as shown and
described.

DESCRIPTION

FIG. 1 is a perspective view of a tire tread showing our
new design it being understood that the pattern is
repeated throughout the circumference thereof;

FIG. 2 is a front elevational view thereof;

FIG. 3 is a side elevational view thereof; and,

FIG. 4 is an enlarged fragmentary front view thereof.
The broken line showing of the tire sidewall in the
drawings is for illustrative purposes only and forms no
part of the claimed design.

FIG-1

FIG-2
